UNITED STATES PATENT OFFICE

ISRAEL SILBERSTEIN, OF BALTIMORE, MARYLAND

DESIGN FOR A PORTABLE CARBON ARC LAMP

Application filed December 10, 1932. Serial No. 46,418. Term of patent 7 years.

To all whom it may concern:

Be it known that I, ISRAEL SILBERSTEIN, a citizen of the United States, residing at Baltimore, in the State of Maryland, have invented a new, original, and ornamental Design for Portable Carbon Arc Lamp, of which the following is a specification, reference being had to the accompanying drawing, forming part thereof, in which:

Fig. 1 is a perspective view of the lamp of my invention with the wings in closed position;

Fig. 2 is a side elevation of the same; Fig. 3 is a front elevation with the wings in closed position, and,

Fig. 4 is a perspective view of the upper portion of the lamp with the wings in open position and the standard shown broken away.

What I claim is:

The ornamental design for a portable carbon arc lamp, substantially as shown and described.

ISRAEL SILBERSTEIN.
